(57) **CLAIM**

An ornamental design for an electronic deadbolt for a door as shown and described.

DESCRIPTION

FIG. 1 is a top perspective view of an electronic deadbolt for a door according to a new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The portions depicted in broken lines form no part of the claimed design.

1 Claim, 7 Drawing Sheets
